His Attorney's.

UNITED STATES PATENT OFFICE.

DELMAR LEWIS JOHNSON, OF ST. LOUIS, MISSOURI.

DESIGN FOR A SIGNAL LENS PLATE.

Application filed December 12, 1921. Serial No. 521,939. Term of patent 7 years.

To all whom it may concern:

Be it known that I, DELMAR LEWIS JOHNSON, a citizen of the United States, residing at the city of St. Louis and State of Missouri, have invented a new, original, and ornamental Design for a Signal Lens Plate, of which the following is a specification, reference being had to the accompanying drawing, forming part thereof.

The figure is a view of an assembly of lens plates for a signal, showing my new design.

In said drawing the shading is only for the purpose of indicating that the areas are distinguishingly colored or shaded and not for the purpose of restriction to any particular colors.

I claim:

The ornamental design for a signal lens plate, as shown.

DELMAR LEWIS JOHNSON.
